FABRICATED METAL BUILDING

Owen M. Stoltz, Dayton, Ohio

Application February 24, 1936, Serial No. 65,345

7 Claims. (Cl. 189—34)

This invention relates to a metal building and more particularly to a wall unit for use in constructing such a building.

One object of the invention is to provide a 5 standardized wall unit and means whereby a plurality of such units may be easily and accurately assembled to form the walls of a building.

A further object of the invention is to provide such a wall unit which will be complete, with interior and exterior wall surfaces, and means for 10 attaching the same to other wall units and to a supporting structure.

A further object of the invention is to provide 15 a wall unit of such a character that the spaces between two such wall units may be filled with concrete or like material to provide a rigid supporting column and to render the joint air tight and moisture proof.

A further object of the invention is to provide 20 a wall unit of such a character that a wall formed from a plurality of such units will be insulated against the transmission of heat or cold.

A further object of the invention is to provide such a wall unit which will be simple in its construction and of such a character that it can be 25 easily manufactured and transported to the place where it is to be used.

Other objects of the invention may appear as the device is described in detail.

In the accompanying drawing Fig. 1 is a 30 perspective view, partly broken away, of a portion of a building showing walls formed of a plurality of units embodying my invention; Fig. 2 is a perspective view, partly broken away, of one of the wall units; Fig. 3 is a transverse section taken through the adjacent edges of two units and the supporting member; Fig. 4 is a sectional detail of the insulated connection between the panels of the wall unit; Fig. 5 is a perspective 35 detail of one of the attaching devices; Fig. 6 is a detail view, partly broken away, of a connecting member for securing a plurality of units to the foundation; and Fig. 7 is a detail view, partly broken away, of a top beam for connecting the several units one to the other and for supporting joists or rafters.

In the drawing I have illustrated one embodiment of my invention and have shown the same as comprising a wall unit having a panel or 40 panels and provided with attaching devices whereby two or more of such panels may be connected one to the other to form a wall, the adjacent edges of adjoining panels being so arranged as to form between them a longitudinal 45 chamber to receive a supporting member, which is preferably provided by filling the chamber with concrete or other plastic material which, when hardened, will form a rigid support.

In the particular construction illustrated each 50 unit comprises an inner panel 16 and an outer

panel 11 arranged in parallel planes and rigidly connected one to the other in spaced relation. The two panels may be connected one to the other in any suitable manner but preferably longitudinal members are arranged between and 5 rigidly secured to the panels near the respective edges of the unit and these connecting members are so spaced with relation to the edges of the unit as to form longitudinal channels, so that when two units are placed edge to edge a longitudinal 10 chamber will be formed between the units. In the form shown these longitudinal members are in the form of outwardly facing channel members 12, the flanges of which are rigidly secured to the respective panels, as by 15 welding. The flanges of the channel members may be secured in direct contact with the panels but in many cases it is desirable to insulate the panels one from the other to prevent the transmission of heat or cold through the wall and for 20 this purpose I prefer to space the flanges 13 of the channel members 12 a short distance from the respective panels and to connect the same to the panels by inserting connecting devices through openings in the flanges and securing the 25 outer ends of these fastening devices to the respective panels, as by welding. As shown in Fig. 4, this connecting device is in the form of a thimble 14 formed from sheet metal and having 30 at its inner end a circumferential flange 15 which overlaps the adjacent portions of the flange 13 of the channel member. The body of the thimble 16 is somewhat smaller than the opening in the flange 10 and a liner 16 of insulating material is 35 interposed between the thimble and the flange 13, and a washer 17 of insulating material is interposed between the flange 13 and the panel. The proportions of the parts are such that when the insulation is in place and the thimble pressed 40 into contact with the panel and welded thereto a very rigid connection will be formed between the channel members and the panels, a sufficient number of connecting devices being used to provide rigidity throughout the length of the unit. In the construction here shown the edges of the 45 panels 16 and 11 are bent or curved inward, as shown at 18, thus providing grooves into which the flanges of the channel members may extend. However, this arrangement, while desirable, is not 50 essential. It is only essential that the channel members should be insulated from one of the panels but more efficient results are secured by insulating both panels from the connecting members, as shown in the drawing.

In erecting the wall the several units are 55 mounted edge to edge on a foundation 19 and a preliminary connection is effected between adjacent units to properly locate the same with relation one to the other and to retain them in their proper positions during the erection of the 60

wall and the insertion of the supporting member. For this purpose I prefer to provide each edge of the unit with one or more attaching devices adapted to have interlocking engagement with corresponding attaching devices carried by an adjacent unit. In the construction shown each attaching device includes resilient parts adapted to be sprung into interlocking engagement with the corresponding attaching device on another unit. In its preferred construction this attaching device consists of a short section of sheet metal bent into substantial channel shape so that it is approximately U-shape in cross section. The attaching device is mounted between the flanges 13 of the channel member and the transverse wall 20 thereof is rigidly secured to the channel member, while the lateral portions 21 of the device project beyond the adjacent edges of the panels and are curved or otherwise shaped, as shown at 22, to enable them to have interlocking connection with the side members of another attaching device. The device may be secured to these channel members in any suitable manner and when the unit is completely fabricated at the factory the attaching device may be welded to the channel member. However, in many cases it is desirable that the attaching devices should not be permanently connected with the channel members at the factory but that they should be removable or adjustable to permit their location to be varied during erection, and I have in the present instance shown the transverse portion of the connecting member as provided with an integral boss 23 formed by extruding a portion of the metal and constituting a rivet adapted to be inserted through one of a series of openings 24 in the channel member and to have its outer end upset to secure the attaching device to the channel member, as shown in Fig. 3. In the arrangement shown each attaching device is provided with two of these rivets but, of course, any suitable number of rivets may be provided. The resilient outer portions of the side members of the attaching device are so spaced that when one unit is moved toward the other one attaching device will enter between the side members of the other and will then spring into interlocking engagement therewith. The attaching members are so constructed and located that when they are in interlocking engagement the units will be located in their proper relative positions, with the panels in alignment one with the other, and will be retained in these positions while the erection of the wall is being completed.

If desired, means may be provided for positively connecting the interlocking attaching devices one to the other. In the arrangement shown the interlocking portions of the attaching devices are so arranged that when they are in interlocking engagement the adjacent edges of the panels of the connected units will be spaced a short distance apart and in Fig. 3 I have shown a fastening device, such as a screw 25, inserted between the edges of the adjacent panels and through the interlocked portions of the two attaching devices, thus preventing any relative movement of the attaching devices.

The corner units, as shown in Fig. 1, are similar in construction to the side units but the inner and outer panels are angular as shown at 26 and 27, so that the channel members 12 are arranged at right angles one to the other.

The several units may be secured to the foundation 19 in any suitable manner. Preferably the outer panel extends below the inner panel so that

it overlaps the foundation, as shown at 28, and in the construction shown a member, such as an angle bar 29, is rigidly secured to the foundation on the inner side of the wall and extends lengthwise thereof across a plurality of units. The several units may be secured to this longitudinal member in any suitable manner, as by extending the screws 25 through the vertical flange of the angle bar, then through the slot between adjacent panels and through the attaching devices. The angle bar may be secured to the foundation in any suitable manner, as by a plate 30, which is clamped onto the horizontal flange of the angle bar by a nut 31 on a bolt 32 which is embedded in the concrete of the foundation. It will be understood that the floor joists which rest upon this foundation extend above the angle bar so that the bar and its associated parts will be beneath the floor level. The vertical supporting columns are preferably secured to the foundation independently of the wall units and this may conveniently be accomplished by embedding in the concrete of the foundation, when the latter is poured, a stud or rod 33, the upper portion of which will extend into the longitudinal chamber between two units and will thus be embedded in the concrete of the supporting member and will rigidly secure the latter to the foundation. The foundation may be provided with a series of these rods spaced apart a distance equal to the width of one of the wall units. However, exact spacing is unnecessary as it is not essential that the anchored rod should be exactly at the center of the supporting column.

When the preliminary connections have been effected and the wall or a desired portion thereof erected, the longitudinal chambers, which are formed between the channel members 12 of adjacent units, are filled with concrete, or other suitable material, which, when hardened, will form a rigid upright supporting member for the units. This concrete completely fills the space between the channel members, and the attaching devices 20 and fastening devices 25 are embedded in the concrete so that the connection between the units becomes permanent. Further, the concrete completely closes the space between the adjacent channel members and the inturned edges of the panels are embedded in the concrete, thus providing a weather proof joint between adjacent units. This construction also prevents any relative movement of the panels and prevents the transmission of vibrations from one panel to another. When the concrete has set and before it has completely hardened these joints are raked to remove the excess concrete from the slots between adjacent panels and form grooves of uniform depth between the panels, which may be filled with plastic material with which the wall surfaces formed by the panels are coated.

The inner panel 10 extends above the outer panel 11, the channel members 12 terminating approximately at the top of the outer panel, and the upper attaching devices extend approximately to the top of the inner panel. In filling the concrete into the longitudinal chambers these chambers are filled to approximately the level of the upper edge of the outer panel and thereafter a top beam, in the form of an inverted channel 33, is placed over the upper portions of the attaching members with its outer flange above and in line with the outer panel 11 and with its inner flange inserted between the attaching members and the upper portion of the inner panel, the curved edge portions 13 of the inner panel be-

ing cut away to permit of the insertion of the flange of the top beam, as shown in Figs. 1 and 2. The panels may then be secured to this top beam by inserting the connecting screws 25 through the flanges of the top beam and into the attaching devices, the screws on the inner side of the wall also extending through the slots between adjacent inner panels. Thereafter, if desired, the chamber between the channel members 12 may be completely filled with concrete by inserting the latter through an opening in the top beam, such as one of a series of openings 34 provided for connecting joists or rafters therewith.

If insulation is desired in addition to that provided between the channel members 12 and the panels, such additional insulation may be inserted between the inner and outer panels and between the two channel members, either by filling this space with loose insulating material or by securing a layer or sheet of insulating material between the channel members.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. A wall unit comprising parallel panels spaced one from the other, outwardly facing channel members arranged between and rigidly secured to said panels near the lateral edges thereof, attaching members secured to said channel members and having resilient parts projecting beyond the edges of said panels and adapted to be sprung into interlocking engagement with corresponding attaching members on other units to retain said units in alignment, with adjacent channel members in juxtaposition to form a vertical chamber adapted to receive a plastic material, and fastening devices to extend between panels of adjacent units and through said interlocking attaching members, said attaching members and portions of said fastening devices being arranged to be embedded in the plastic material in said chamber.

2. In a wall for a metal building, a plurality of units arranged edge to edge and each comprising inner and outer panels spaced one from the other, longitudinal members arranged between and rigidly secured to said panels, said members being spaced from the lateral edges of said panels to form between the edge portions of the two panels channels adapted to receive a portion of a supporting member, the outer panel extending below the inner panel to overlap the foundation and the inner panel extending above the outer panel, and a channel-shaped top beam having its outer flange in substantially the same plane with the outer panels of said units and having its inner flange overlapping the inner panels.

3. A metal wall for a building comprising a plurality of units mounted edge to edge on a foundation, each unit including inner and outer panels rigidly connected one to the other in spaced relation, the outer panel of each unit overlapping said foundation, each unit having a vertical channel in each lateral edge thereof, means for connecting said units one to the other with said channels in opposed relation to form longitudinal chambers between adjacent units, a member secured to said foundation and extending across a plurality of said units, means for securing said units to said member, an inverted channel mem-

ber mounted on the upper portions of and extending across a plurality of said units, the inner panel of each of said units overlapping said channel member, and means for securing said units to said channel member.

4. A metal wall for a building comprising a plurality of prefabricated units adapted to be mounted edge to edge on a foundation and having longitudinal channels in their adjacent edges, said units being movable edgewise on said foundation to locate the edge of one unit in close proximity to the edge of an adjacent unit and form between said units a vertical chamber, said chamber being filled with hardened plastic material, attaching devices mounted in said channels, extending beyond the edges of the respective units and so arranged that the edgewise movement of one unit toward an adjacent unit will bring the attaching devices on said units into cooperating engagement to effect a preliminary connection between said units and retain said units in their proper relative positions, and an anchor secured to said foundation and extending into the lower end of said chamber in spaced relation to the walls thereof, whereby said anchor and said attaching devices will be embedded in said plastic material to permanently connect said units one to the other and to said foundation.

5. In a metal wall, a plurality of units arranged edge to edge, each unit comprising inner and outer panels spaced one from the other and a longitudinal member arranged between and rigidly secured to said panels, said member being spaced from the lateral edges of said panels at one edge of said unit to form a channel between the edge portions of the two panels, said units being movable lengthwise of a supporting structure to position the channel of one unit in close proximity to the channel of an adjacent unit and form between said units a longitudinal chamber, attaching devices mounted in the channels of the respective units and so arranged that said edgewise movement of one unit will operatively engage the attaching device of that unit with the attaching device of said adjacent unit to establish a preliminary connection between said units, and hardened plastic material substantially filling said longitudinal chamber and surrounding said attaching devices to support said units and to convert said preliminary connection into a permanent connection.

6. In a metal wall comprising two upright units having opposed vertical channels forming between them a longitudinal chamber, attaching devices secured to the respective units within said channels and having engagement one with the other in said chamber to effect a preliminary connection between said members and hold the same against relative lateral displacement, hardened plastic material substantially filling said chamber, surrounding said attaching devices and forming a supporting column for said units, and means for securing said column to a structure on which said upright members are supported.

7. A metal wall comprising upright panels arranged edge to edge and having opposed longitudinal channels forming a vertical chamber between said panels, attaching devices mounted in the respective channels and having vertically overlapping parts, and a fastening device extending between adjacent edges of said channels and through the overlapping parts of said attaching devices to secure the latter one to the other.
